UNITED STATES PATENT OFFICE.

BERNHARD DREYFUS, OF NEW YORK, N. Y.

DESIGN FOR A PENDANT.

SPECIFICATION forming part of Design No. 15,529, dated November 11, 1884.

Application filed May 7, 1884. Term of patent 7 years.

To all whom it may concern:

Be it known that I, BERNHARD DREYFUS, of the city, county, and State of New York, have invented and produced a new and original Design for a Pendant-Head, of which the following is a full, clear, and exact description, reference being had to the accompanying drawing, forming a part of this specification, in which a face view of my design is shown.

10 A is a cap having the shape of an umbrella, and having cords C on the ribbed portion of the outer surface. D is a tuft or ball at the mouth of the cap. E is a tuft or ball on the top of the cap, and F is a loop on the tuft or ball E.

15 I claim—

1. The herein-described design for a pendant-head, consisting of a pendant-head having the shape of an umbrella and displaying a tuft or ball at its mouth, as shown.
20 2. The herein-described design for a pend-

ant-head, consisting of a pendant-head having the shape of an umbrella, showing cords C on the ribbed portion of its outer surface, and a ball or tuft, D, at its mouth, as shown.

25

3. The herein-described design for a pendant-head, consisting of a pendant-head having the shape of an umbrella, showing cords C on the ribbed portion of its outer surface, the tuft or ball D at its mouth, and the tuft or ball E on its top, as shown.

30

4. The herein-described design for a pendant-head, consisting of a pendant-head having the shape of an umbrella, showing the cords C on the ribbed outer portion, the tuft or ball D at its mouth, the tuft or ball E on its top, and the loop F on the tuft or ball E, as shown.
